PILLOW SPEAKER

Ludwig Arnson, New York, N. Y.

Application March 19, 1932. Serial No. 599,905

3 Claims. (Cl. 179—182)

This invention relates to a pillow which is especially constructed to receive the earphone of a radio or telephone receiver, and which is particularly applicable for use by persons who are confined to their beds or otherwise incapacitated and who because of their location in a hospital or home may not be in a position to receive radio programs by way of a loud speaker.

Pillows embodying receiving units have been devised, but in all known constructions the hard receiving instrument is attached to the wall of the pillow directly under and in contact with the patient's head and ear. In other instances the earphones are actually built into the pillow structures. The result has been, therefore, a pillow which is extremely uncomfortable for the patient as well as unsanitary since an instrument arranged inside a pillow does not lend itself well to being removed while the pillow is being sterilized.

With the foregoing in mind it is the purpose of the present invention to overcome any difficulties heretofore experienced and to provide an inflated pillow, which accommodates a receiving unit in a pocket arranged on its underside and away from the head and which is further provided with an opening projecting through the center of the pillow and in communication with the receiving unit at one end and with the region under the ear of the patient at the other end, so that none of the comforts afforded by a pillow will be sacrificed for the sake of accommodating a receiver and being able to receive radio programs.

I accomplish this purpose by means of the arrangement and combination of parts herein-after described in the specification set forth in the appended claims, and illustratively exemplified in the accompanying drawing, in which, Figure 1 is a top plan view of a pillow having the receiving unit in place; Figure 2 is a substantially transverse sectional view of the pillow taken on lines 2—2 of Figure 1; and Figure 3 is an elevational view of a portion of the underside of the pillow showing the pocket construction and receiving unit enclosed therein.

Referring to the drawing, the pillow comprises a casing made up of an upper wall 10 and a lower wall 11, both of which are a rubberized material which allows the pillow to be inflated and thoroughly sterilized after use. The sheets or walls, 10 and 11 are secured together about their marginal portions in any convenient manner and at one corner a valve 12 is incorporated to enable the pillow to be inflated. Communication

through the pillow is established by punching or otherwise making an opening in the two walls 10 and 11 preferably at the midportions thereof. An eyelet 13 is then inserted in the opening and the flanges clamped together over the edges of the upper and lower walls to form an airtight joint at this point, as illustratively exemplified in Figure 2. A pocket is built into the underside 11 of the pillow by stitching a piece of material 14 marginally thereof with the exception of one side to the outer surface of the under wall 11 at a point directly over the eyelet 13. A closure for the pocket is provided by stitching another piece 15 to the under wall 11 beyond the piece 14, which is provided with one section of a separable fastener 16, the other section being carried by the cover 15, as illustrated in Figures 2 and 3. The pocket accommodates an ear piece 17 of any well known type from which a flexible cord 18 leads out of the pocket the free end of the cord being provided with a plug 19 adapted to be inserted into the phone jack of any radio receiving set.

In use, the receiver 17 is inserted in the pocket of the pillow, which has already been inflated, so as to bring the opening in the instrument directly in line with the opening through the pillow formed by the eyelet 13. The cord 18 emerges from beneath the pocket cover 15 and is plugged into a wall jack or into the jack of the dial panel of a radio receiving set. The nurse or attendant may make the proper volume adjustment in the receiving instrument 17 before placing the pillow beneath the patient's head. In the arrangement of the pillow, according to the present invention, it will be particularly noted that the pocket side is intended to be the underside and that the soft unobstructed upper face with simply the depressed center portion to accommodate the eyelet 13 will support the head in the most comfortable and natural position afforded by the usual type of pillow.

Having described my invention, what I claim as new and desire to secure by Letters Patent is:

1. A pillow of the character described comprising a casing having an unobstructed opening from one side to the other, a rigid binding for the opening, a depression on each side adjacent the opening, a pocket formed by one depression to receive a receiver larger than the opening and a closure for the pocket.

2. A pillow of the character described comprising a casing having an unobstructed opening from one side to the other, a depression on each side adjacent the opening, a pocket formed by

100

110

one depression to receive a receiver larger than the opening and a closure for the pocket comprising a flap permanently attached on three sides and a second flap permanently attached on three sides and having its free side overlapping the free side of the first mentioned flap and means for detachably connecting the overlying free sides.

3. A pillow of the character described, comprising a casing made up of superimposed layers of flexible material impervious to air attached together at their margins, a valve carried by the

casing between the layers and in communication with the interior to admit air, each layer being provided with an opening at its midportion, an eyelet embracing the walls of the openings to form an open sound passage from one side of the pillow to the other, and a pocket adjacent the eyelet on one side of the pillow to receive a telephone receiver larger than the eyelet hole, a cover for the pocket and detachable means for opening the pocket to remove the receiver.
